[57] CLAIM

The ornamental design for a portion of a shoe upper, as shown and described.

DESCRIPTION

FIG. 1 is a top plan view of a portion of a shoe upper showing my new design;

FIG. 2 is a side elevational view showing one side thereof;

FIG. 3 is a side elevational view showing the other side thereof;

FIG. 4 is a front elevational view thereof;

FIG. 5 is a front perspective view from one side thereof; and,

FIG. 6 is a front perspective view from the other side thereof.

The uneven broken line showing of the shoe sole and the remaining portions of the shoe upper in FIGS. 1-6 is for illustrative purposes only and forms no part of the claimed design.
